UNITED STATES PATENT OFFICE

122,077

DESIGN FOR A RADIATOR GRILLE FOR A VEHICLE

Vincent D. Kaptur, Detroit, Mich., assignor to General Motors Corporation, Detroit, Mich., a corporation of Delaware

Application May 27, 1940, Serial No. 92,646

Term of patent 7 years

To all whom it may concern:

Be it known that I, Vincent D. Kaptur, a citizen of the United States and a resident of Detroit, county of Wayne, and State of Michigan, have invented a new, original, and ornamental Design for a Radiator Grille for a Vehicle, of which the following is a specification, reference being made to the accompanying drawing, forming a part thereof, in which

I claim:

The ornamental design for a radiator grille for a vehicle, as shown.

VINCENT D. KAPTUR.
